UNITED STATES PATENT OFFICE.

CHARLES H. HERRICK, OF CLEVELAND, OHIO, ASSIGNOR TO PECK, STOW AND WILCOX COMPANY, OF CLEVELAND, OHIO, A CORPORATION.

DESIGN FOR A DOOR-KNOB.

No. 39,779.

Specification for Design.

Patented Jan. 19, 1908.

Application filed July 3, 1908. Serial No. 441,923. Term of patent 7 years.

To all whom it may concern:

Be it known that I, CHARLES H. HERRICK, of the city of Cleveland, county of Cuyahoga, and State of Ohio, have invented a new, original, and ornamental Design in a Door-Knob, of which the following is a specification when taken in connection with the accompanying drawings, which form a part thereof, and in which—

Figure 1 represents a front elevation of a

door knob embodying my new, original and ornamental design, and Fig. 2 represents the door-knob in side elevation.

What I claim is;—

The ornamental design for a door knob, as shown.

CHARLES H. HERRICK.
